CARD GAME BOARD

Herbert B. Taylor, Rochester, N. Y.
Application May 28, 1934, Serial No. 727,915

13 Claims. (Cl. 273—151)

This invention relates in general to amusement devices and more particularly to card game boards or tables for facilitating the playing of well known card games in duplicate, such as contract and auction bridge, five hundred and pinochle.

The manner of playing the more popular card games is considered well known, but in order to more clearly set forth the objects and purposes of the present invention, it will be stated in a very general manner that, in playing duplicate contract bridge, for example, thirteen cards are distributed to each of four players, the two opposite players being partners, and tricks are then played by each player's placing one card in an individual place in front of themselves with the partners winning the tricks placing their cards face down in some position indicating that such tricks are theirs. After thirteen tricks are thus played and the winnings or losses of each of the partners are recorded, each player collects his original cards which are later to be replayed in the same manner, but in replaying, these cards are played by their opponents and the partners recording the greater number of points with the same cards are the winners.

However as such duplicate games are usually played, the decks of cards are not immediately replayed after originally being played, but several decks of cards say sixteen are originally played in succession with the cards of each deck stored in their original four groups of thirteen and the several decks are later replayed in succession, thereby obviating the possibility of the players remembering their opponent's cards when replaying the decks. Heretofore, the means for storing the groups of cards has for example been a small board having four individual pockets or recesses into which the thirteen cards after being originally played are placed by each player, and these pockets are associated with the original players of the cards therein by suitable markings so that in later replaying, the board is rotated ninety degrees from its original position, thereby exchanging the groups of cards among the players.

Inasmuch as these small boards hold only a single deck of cards, the original playing of a considerable number of decks in succession obviously necessitates the inconvenience of removing the filled board and substituting an empty board after the original playing of each deck, and conversely after the duplicate playing of each deck. It is also obvious that when a board of this type is required for each deck of cards, the num-

ber of boards required for proper playing of duplicate card games becomes very cumbersome, and the groups of cards are often inserted therein in improper relationship.

In view of the above and other considerations, it is proposed in accordance with the present invention to provide a duplicate card game device permitting the original playing of a plurality of decks of cards without the objectional use of an individual board for storing the groups of cards of each of such decks until the subsequent replaying thereof. More specifically, it is proposed to provide a single device such as a board or table having a movable card storing means or magazine, wherein the groups of cards of each of a plurality of decks may be successively stored as they are originally being played and later removed in the same or any other succession when they are being replayed. Furthermore, it is proposed to provide means whereby the groups of cards of any one deck can only be stored or removed at a time, and wherein the storing or removing of the groups of each deck may be performed in a manner so convenient to the players that improper exchanging of the various groups is obviated.

It is further proposed to provide a means cooperating with such a movable magazine for continuously indicating to each player the number of the particular deck being played, and other means for conveying certain other information useful in playing the particular game in duplicate. Other objects include the provision of a means for ejecting from the magazine the next group of cards to be played in a convenient manner to each of the players, and the provision of a means for retaining a definite position of the magazine and for retaining the unreplayed cards therein in the event the board is to be removed from play and completed at a later time.

Still other objects, purposes and characteristic features of the present invention will appear as the description thereof progresses, during which, references will be made to the accompanying drawings; in which:

Fig. 1 is a plan view of a device constructed in accordance with the present invention with certain parts broken away to more clearly show certain novel features.

Fig. 2 is an elevational view of Fig. 1 also having certain parts broken away.

Fig. 3 is an enlarged elevational section of a portion of Fig. 1 taken substantially on line 3—3 and viewed in the direction indicated by the arrows.

Fig. 4 is an enlarged elevational section of another portion of Fig. 1 taken on line 4-4 and viewed in the direction indicated by the arrows.

Fig. 5 is enlarged elevational section of still another portion of Fig. 1 taken on line 5-5 and viewed in the direction indicated by the arrows.

Fig. 6 is an enlarged plan view illustrating how a portion of the device shown in Fig. 1 may be modified, and certain parts have also been broken away in this view to more clearly show the construction thereof.

Fig. 7 is an elevational section of Fig. 6 taken on line 7-7 and viewed in the direction indicated by the arrows.

Fig. 8 is a plan view of a modified form of the present invention with certain parts also broken away to more clearly show the construction thereof.

Fig. 9 is an elevational view of Fig. 8 also having certain parts removed.

Referring particularly to Fig. 1 and Fig. 2 of the accompanying drawings, the present card game board is assembled about a substantially square base plate 21 which may be of wood, card board, metal or any suitable sheet material. Four corner frame members 22, 23, 24 and 25 of wood or the like are individually secured upon the four corners of the base plate 21 in any suitable manner such as by rivets 26, and the inside edges 30 of each of these members are shaped as shown in Fig. 1 to form in combination a substantially perfect circle when assembled upon the base plate 21.

A card holding magazine M rotates above the base plate 21 and within the circle thus formed by the edges of the frame members 22, 23, 24 and 25, which magazine M is formed of three circular rings 27, 28 and 29 of material such as the base plate 21 for example, the rings 27 and 28 being separated vertically by thirty-two equally spaced separators 30 and the rings 28 and 29 being spaced by thirty-two evenly spaced similar separators 31. The separators 30 and 31 are all arranged radially between their respective rings, each separator 30 being placed above and in the center of the space between the upper separators 31 as may be seen in Fig. 2, and the separators 30 as well as the separators 31 are spaced to easily receive an ordinary playing card C, while the height of these separators 30 and 31 is sufficient to easily receive a pile of thirteen of such playing cards. The rings 27, 28 and 29 and the separators 30 and 31 may be held together in any suitable manner to thus form a rotatable magazine M, such as for example by rivets 32, some passing through the ring 27, separator 30 and ring 28; and others passing through the ring 28, separators 31 and ring 29 as suggested in Fig. 3 and Fig. 5.

In order to retain the cards C within the magazine M and to form an inner bearing for the magazine M, four like sectors 36 of wood or the like are fixed to the base plate 21, such as by rivets 37, which sectors 36 fit within the inside of the magazine M or rings 27, 28 and 29, yet allow the magazine M to freely rotate. The bottom ring 27 is provided with semi-circular notches 38 throughout at least one quarter of its diameter, which notches register with interfitting teeth 39 of a disc 40 rotatable about a stud 41 having an enlarged flat lower end fitting into a recess in the base plate 21 whereby it is fastened by rivets 42 as shown in Fig. 3.

The toothed disc 40 is carried within a cut-away portion of the frame member 25, and an

opening in the right hand side of the frame member 25 as seen in Fig. 1 communicates with the disc 40 in a manner to permit rotation thereof by the hand of the operator, which rotation obviously effects rotation of the magazine M through the medium of the notches 38 and teeth 39. A flat spring member 43 is fastened to the frame member 25 by screws 44 and coacts with the teeth 39 of the disc 40 in a manner to effect a detent whereby the magazine M is held against accidental rotation and also serving to indicate to the operator by feel that the magazine M has been rotated one division. It is contemplated that the disc 40 may in some cases be provided with upwardly extending webs or pins on each 15 of the teeth 39 to permit easier manual operation of the disc 40.

The ends of the frame members 22, 23, 24 and 25 do not join, but rather a space is left there-between as may be seen in Fig. 1 which form 20 apertures permitting the cards C to be freely inserted into or removed from the magazine M at midpoints of each edge of the present playing card table, or at points in front of each player. It will now be obvious that certain parts of the present device must be so arranged that, at any one position of the magazine M as arrested by the detent 43, four groups of cards C may be inserted or removed from the magazine M through these respective apertures in the edge of each 30 side of the board, and after the disc 40 is rotated to the next notch and again arrested by the detent 43, the four adjacent groups of cards C may then be inserted or removed in like manner. It will of course be obvious that, due to the staggering of the groups of cards within the magazine M, the successive groups of cards C are alternately removed from first the upper tier of groups 35 as spaced by separators 31 and then from the lower tier as spaced by separators 30.

In order to facilitate the removal of the cards C from the magazine M, an ejector has been provided which, as shown in Fig. 1 and Fig. 5, comprises a knurled cylinder 46 rotatable about a pin 47 attached to the center of the base plate 21 by rivets 48, which cylinder 46 carries a four lobe cam 49 which may be integral therewith. Each of the four lobes of the cam 49 acts on an associated one of four push rods 50 through rollers 51 engaging the edge of the cam 49 and 50 rotatably held within bifurcated ends of their respective push rods 50. The push rods 50 are guided to permit longitudinal movement by an upper and a lower half bearings 52 and 53 respectively, the half bearings being in the form of rings 55 which are secured to the base plate 21 by through rivets 54. The push rods 50 have spade-shaped outer ends 55 as shown in Fig. 5, which are guided between the respective separated ends of the sectors 36, and each of the rings 27, 28 and 29 have spaced slots 56 in the inner edges thereof, one of the slots 56 alining with the spade-shaped end 55 of each push rod 50 at each position of the magazine M as arrested by the detent 43. In other words, each of the rings 65 27, 28 and 29 have slots 56 alining with each of the separators 30 and interposed therebetween are like slots 56 which aline with each of the separators 31, the separators 30 and 31 extending inwardly only to the end of the slots 56 as shown 70 in Fig. 1 and Fig. 5.

It will now be obvious that if the cylinder 46 is manually turned ninety degrees in either direction the lobes of the cam 49 will force each of the push rods 50 outwardly so that the spade-shaped 75

ends thereof will enter the slots 56 and partially eject the groups of cards C from the magazine M through the openings in each of the four edges of the board. For example, considering that the magazine M is positioned as shown in Fig. 1 so that a group of cards in the upper tier thereof, or those spaced by separators 31, aline with the opening in the left hand side of the board, the ends 55 of the push rods in moving outwardly will engage and partially eject the group of cards C which are in the upper tier, but will pass in the space between two adjacent lower groups separated by one of the spacers 30. A compression spring 57 is provided on each push rod 50 with one end engaging the inside edges of the sectors 36 and the other end acting upon rings 58 attached to the respective push rods 50 in a manner to return each of these push rods 50 to their inner position as shown after the cam 49 has completed its ninety degree rotation. If it is found desirable to retain the rods 50 in their outer position while playing the ejected groups of cards in order to insure against accidental rotation, the lobes of the cam 49 may have cup-shaped ends for receiving and retaining the rollers 51, thereby effecting that the cylinder 46 is mechanically retained when rotated forty-five degrees to hold the ends 55 of the push rods within the slots 56.

The board thus formed is covered by a top plate 59 of substantially the same shape and may be of the same material as the base plate 21, and this top plate 59 may be fastened at the center by screws 60 threaded into the upper bearing members 52 and at the edges by screws 61 threaded into the respective sectors 36 and corner frames 22, 23, 24 and 25 as shown in Fig. 1. A cover sheet 62 of felt, cloth or any other material having a surface suitable for card tables is secured to completely cover the top plate 59 such as by a suitable glue or cement. A substantially funnel-shaped depression may be formed in the center of this top sheet 59 and cover sheet 62 with a hole in the center thereof receiving the ejector operating cylinder 46 to permit operation thereof as shown in Fig. 5.

The top ring 29 of the magazine M is provided with an arcuate slot 63 positioned as shown in Fig. 1, and a pin 64 is attached to the cover plate 59 in the manner shown in Fig. 4 so that its downwardly extending end is received within the slot 63 thereby limiting the rotation of the magazine M to slightly less than ninety degrees. It will now be obvious that each quarter of the magazine M contains sixteen overlapping spaces, and the slot 63 is to be of a length just permitting these sixteen spaces to be consecutively positioned to allow the player associated with each quarter to insert a group of thirteen playing cards in each space. In other words, at each position of the magazine M, the four players can insert an aggregate of fifty-two cards or a complete deck, thereby providing that, throughout the rotation of the magazine M as permitted by slot 63, sixteen decks of cards C may be inserted.

It is often desirable to remove the board or table in duplicate games after the sixteen decks of cards have thus been inserted in the magazine, and to permit moving of the board without losing any of the cards therefrom, a locking means has been incorporated which is operable to retain the magazine M in an intermediate position which will not permit the removal of any cards therefrom. Such a locking means is herein provided

by a cylinder 68 (see Fig. 3) which is threaded upon the upwardly extending end of the stud 41, and is provided with a flanged lower end which is separated from the top of the disc 40 by a frictional washer 69 of any suitable material such as cork, rubber or felt.

The upper end of the cylinder 68 may have a knurled outer surface which extends through a hole in a funnel-shaped depression formed in the top plate 59 and cover 62, so that the top of 10 the cylinder 68 extends upwardly to about the level of the top plate 59. During the normal operation of the present device, the cylinder 68 is free of the washer 69, but when the device is to be removed from play, the magazine M is first 15 moved to an intermediate position wherein the cards C cannot be removed, and then the threaded cylinder 68 is turned by a player in a manner to force the frictional washer 69 downwardly, thereby forcing the disc 40 against the base plate 20 21 sufficiently to prevent movement of the magazine M until released at a time when playing is to be resumed.

A means for continuously indicating to one of the players, preferably the dealer, the number of 25 the particular deck being played is provided in the present embodiment of the invention by a series of numerals from 1 to 16 inclusive suitably placed on the top of the top circular ring 29 as shown in Fig. 1, one numeral being placed 30 above each of the sixteen card spaces included in one quarter of the magazine M. A window 70 is provided directly in front of one of the players, preferably the dealer, by a hole through both the cover sheet 62 and the top plate 59, through 35 which window 70, the above mentioned numerals become visible consecutively throughout the permitted rotation of the magazine M, one of the numerals being visible, of course, at each position of the magazine as stopped by the detent 43. 40

A means for conveying information to each of the four players which is considered useful in playing the particular card game has also been provided by a series of spots or discs 71 also suitably applied to the top of the ring 29 so as to 45 be spaced inwardly from the numerals but alining radially therewith. The complete number of these discs have not been shown throughout the circumference of the magazine M, but it is to be understood that a disc 71 is provided above 50 each of the sixty-four card spaces included in the complete magazine as is illustrated by the quarter portion of the magazine M which is exposed in Fig. 1. A window 72 is provided in front of each of the four players by a hole through 55 both the cover sheet 62 and the top plate 59 registering with the alinement of the discs 71, through which windows 72 certain ones of the discs 71 appear consecutively to each of the four players in the same manner as the above mentioned numerals appear through the window 70 to the dealer.

The information to be conveyed to the players by the discs 71 will of course depend on the particular game for which the present device is intended, but for example in playing contract bridge, some of these discs 71 may be white and others red, with some of the white discs and also some of the red discs marked with the character D. The manner in which such distinctively 70 marked discs can be arranged about the magazine M to convey information of the status of the game to each of the players will be obvious to those familiar with the game of auction bridge, but to set forth the utility of an indicating means, 75

- it may be stated briefly in the terms used by players that, when deck or "hand" number 1 is being played, the discs 71 may be so arranged that a white disc bearing a character D appears before the operator who is the player positioned at the lower side of the board as illustrated in Fig. 1, and plain white discs appear before the other three players, to thereby indicate that the operator is the dealer and that no players are "vulnerable". When the magazine M is rotated to "hand" number 2 however, the discs 71 which appear are arranged so that a red disc bearing the character D appears before the player at the left of the operator and a plain red disc before his partner, while plain white discs appear before both the operator and his partner, thus indicating that the player at the left is the dealer and that he and his partner only are "vulnerable".
- 20: In like manner, when the magazine M is rotated to "hand" number 3, a red disc bearing the character D appears before the operator's partner, a plain red disc before the operator and plain white discs before the other two partners thus indicating that the operator's partner is dealer and that he and the operator only are "vulnerable"; and when "hand" number 4 appears, a red disc having a character D appears before the player at the right of the operator while a plain red disc appears to all other players thus indicating the dealer and that all players are "vulnerable". The arrangement of the discs associated with the remainder of the sixteen "hands" is the same in groups of four as for the first four "hands" described, or that is, "hands" 5, 6, 7, 8 and 9, 10, 11, 12 and 13, 14, 15, 16 are arranged respectively the same in each group as the group 1, 2, 3, 4.
- It is sometimes found desirable to withhold the knowledge of the number of the deck or "hand" from the players until after it has been played, and although it is obvious that some means for covering the window 70 in playing such as the coincidental score pad or the like may be used, it is found that such a covering interferes with the proper placing of the playing cards. For this and other reasons, the modified form of indicating means shown in Fig. 6 and Fig. 7 has been disclosed as an alternative form of a portion of the present invention.
- 50: In Fig. 6 and Fig. 7, a toothed disc 76 is shown which is substantially the same as the disc 40 of Fig. 1 and is intended to cooperate with the other parts of the present device in the same manner. However, the disc 76 is provided with a small concentric gear wheel 77 which may be integral therewith or a separate wheel suitably attached to the top surface thereof. The teeth of the gear wheel 77 mesh at one point with teeth around an inwardly extending lower flange of an eccentrically located indicating cylinder 78 which is provided with an outwardly extending upper flange 79, which flange 79 is rotatably held beneath the top plate 59 by a bezel ring 80 attached to the top plate 59 by rivets 81. Numerals from 1 to 16 inclusive are suitably applied around the top surface of the flange 79, which numerals become visible consecutively during a revolution of the cylinder 78 through a window 82 formed by a hole through the lower right hand corner of the top plate 59 and cover sheet 62. It is of course understood that the parts of the board not shown in Fig. 6 and Fig. 7 may be substantially the same as in the form shown in Fig. 1 with the exception of the numerals on the mag-

azine M and the window 70 which are to be omitted in view of the numerals on the flange 79 and window 82.

The gear wheel 77 is shown as having twelve teeth and the indicating cylinder 78 as having sixteen teeth, or any ratio of teeth can be provided thereon which will result in less than a complete rotation of the cylinder 78 to consecutively position the sixteen numerals on the indicating cylinder 78 beneath the window 82 in accordance with the consecutive positioning of the sixteen decks of cards before the openings of the four edges of the board. A modified means for indicating the position of the magazine M is thereby provided which permits such information to be displayed in a remote corner of the board thereby obviating its interference with the playing of the cards.

It is contemplated that a card game board or table may be provided in accordance with the present invention which is considerably less expensive to manufacture by the simplified arrangement shown in Fig. 8 and Fig. 9. In this form the component parts are the same as corresponding parts of the form shown in Fig. 1, except that each of the three rings 27, 28 and 29 of the magazine M is provided with semi-circular notches 38 which extend throughout the periphery of each, thereby permitting any one of the players to rotate the magazine M by placing a finger through one of the openings in the edge of the board and pushing on a notch 38 in the desired direction of rotation.

A flat spring strip 85 is secured at one end to the inner edge of the corner frame member 22 of Fig. 8 by a screw 86, with the other end of the strip 85 extending inwardly through an opening in the frame member 22 and shaped to enter the notches 38. The spring strip 85 being slightly biased against the magazine M thereby forms a detent which acts to arrest the rotation of the magazine M in the same manner as detent 43 in Fig. 1, or whenever card spaces therein align with the four openings in the edges of the board. The top plate 59 and base plate 21 have been cut away slightly in the form shown in Fig. 8 at positions registering with the openings in the edges of the board to facilitate in the removal of cards from the magazine M inasmuch as the ejecting means shown in Fig. 1 has been omitted in this simpler form. In order to support the center of the top plate 59 in Fig. 8, a spacing disc 87 is attached to the center of the base plate 21 by rivets 88 and the top plate 59 is attached thereto by a screw 89.

In describing the present invention the various forms have been referred to as card game boards which obviously require a support in being used, such as an ordinary card table, but it is contemplated that these devices may also be provided with legs such as suggested by member 90 in Fig. 9 which may be either stationary or folding in any well known manner to thus provide a unitary card game table.

A device for facilitating the playing of duplicate card games has thus been provided which permits the original playing of several decks of cards, each deck being inserted in groups into a magazine which is then rotated to retain the arrangement thereof and to permit the insertion of the next deck therein. In this manner, the original arrangement of the various decks as well as the relative order of playing the decks is preserved until replaying so that confusion is impossible. The replaying of the cards is easily per-

formed in the present device by returning the magazine to its starting position and rotating the device ninety degrees to exchange the groups of cards among the players, after which the original groups of cards of the various decks may be conveniently removed and played in their original sequence or in any other order desired.

Attention is particularly directed to the feature of the present invention whereby certain information useful in playing the particular game is simultaneously placed before each of the players. Although this feature has been shown in combination with a rotatably card storing magazine, it is probable that an arrangement of this type may be incorporated in a rotatable member provided for this function alone in other card game boards or tables. It is further contemplated that the character of the information conveyed by this arrangement may be modified to the various requirements of particular rules or methods of playing various games, the particular arrangement which is shown and described for the numerals and spots or discs 71 being merely to illustrate their utility.

Various other features shown and described which contribute to the convenience of playing the card games, such as the card ejecting means, the magazine rotating disc, and the magazine locking means, cooperate to form the preferred embodiment of the present invention, but it is understood that considerably simpler embodiments may be provided to meet the possible demand for a lower cost device.

However, in order to simplify the disclosure of the present invention, attention has been directed to only a few specific embodiments thereof, without attempting to point out all the various alternate or optional features of construction, or all the different organizations or combinations that may be employed. For example, the card storing magazine in the forms shown have a capacity of sixteen decks of cards, which obviously could be arranged in different proportions to hold a different number of decks, and the specific construction shown is particularly adaptable to the materials used, but if other materials such as spot welded metal stampings are employed, considerable modification would be necessary.

In other words, the particular embodiments of the present invention have been selected to facilitate in the disclosure thereof rather than to limit the number of forms which it may assume.

What I claim is:—

1. In a device for playing duplicate card games, a rotatable magazine, upper card storing pockets around the magazine, lower card storing pockets around the magazine interspaced midway between the upper pockets, and a housing for said magazine having openings communicating alternately with the upper and lower pockets during rotation of the magazine.

2. In a device for playing duplicate card games, a rotatable magazine, upper card storing pockets around the magazine, lower card storing pockets around the magazine interspaced midway between the upper pockets, and a housing for said magazine having four equally spaced openings therein which communicate with four of the pockets at definite positions of the magazine.

3. A device for playing duplicate card games having a rotatable magazine, a four-sided housing for the magazine, a passage in the center of each side of the housing communicating with the magazine, a plurality of card storing apartments in the magazine associated with each pas-

sage, and a toothed wheel manually operable from a side of the housing to rotate the magazine to various sequential positions wherein each of the apartments registers sequentially with the associated passages.

4. A device for playing duplicate card games having a rotatable magazine, a four-sided housing for the magazine, a passage in the center of each side of the housing communicating with the magazine, a plurality of flat overlapping card storing apartments in the magazine associated with each passage, means for manually rotating the magazine to various sequential positions wherein each of the apartments register sequentially with the associated passage, a window in the top of the housing, and indicators on the magazine registering with the window at each of said sequential positions of the magazine.

5. A device for playing card games having in combination, a rotatable magazine, a four-sided housing for the magazine having an aperture in each side, a plurality of overlapping spaced card storing pockets in the magazine, notches in the magazine spaced in accordance with the spacing of the card storing pockets, and a detent acting on the notches in a manner to arrest rotation of the magazine at various positions wherein cards may be inserted through each aperture into one of the pockets registering therewith.

6. In combination, a card game board, a movable magazine within the board wherein a plurality of decks of cards may be stored in a flat overlapping manner, communicating means equally spaced about the edges of the board permitting cards to be inserted into the magazine, manual operating means for moving the magazine to definite positions associated with the storing of each deck of cards, a deck indicating window in the board, a series of numerals positioned on the magazine to be sequentially visible through the deck indicating window as the magazine is manually moved to said definite positions, a status indicating window associated with each communicating means and definitely characterized indicators positioned on the magazine to be visible through the status indicating window at the various definite positions of the magazine.

7. A card game board having in combination, a movable member having apartments for holding a plurality of decks of cards, a housing for the movable member permitting the insertion or withdrawal of one deck of cards only at any one position of the movable member, an operating means for the movable member, and a manually operable lock at times preventing movement of the operating means.

8. A card game board having in combination, a rotatable magazine, an enclosure for the magazine, and indicating means in the inclosure for disclosing the rotated position of the magazine, said indicating means being remotely positioned with respect to the magazine.

9. In a device for use in playing duplicate card games, a magazine rotatably held within a housing, a series of horizontal overlapping pockets within the magazine selectively registering with openings in sides of the housing in accordance with the rotated position of the magazine, a window in the top of the housing, and a series of numerals positioned on the magazine to appear consecutively in the window at the various rotated positions of the magazine.

10. In a device for use in playing duplicate card games, a rotatable magazine, a plurality of horizontal overlapping card storing pockets in

the magazine, a housing for the magazine having four equally spaced openings therein communicating with four of the pockets at definite positions of the magazine, a window in the housing above each of the four openings, and a plurality of differently characterized indicators positioned on the magazine to appear in prearranged cycles before each of the windows at the various positions of the magazine, said cycles being arranged to present differently characterized indicators at different windows.

11. In a device for use in playing duplicate card games, a rotatable magazine, an upper tier of card storing pockets around the magazine, a lower tier of card storing pockets around the magazine interspaced midway between the card storing pockets of the upper tier, a housing for said magazine having openings communicating alternately with the card storing pockets of the

upper and lower tiers during rotation of the magazine, and a manually operable ejector passing between two card storing pockets of one tier to eject cards in the other tier through the openings in the housing.

12. In a card game device, a circular rotatable magazine, a plurality of interspaced tiers of card carrying pockets in the magazine, and a housing for the magazine having openings for withdrawing the cards from the pockets of the magazine, said openings permitting manual rotation of the magazine.

13. In a card game device, a rotatable magazine, interspaced upper and lower tiers of card carrying pockets in the magazine, and an enclosure for the magazine having openings communicating with the card carrying pockets of the magazine.

HERBERT B. TAYLOR.
